UNITED STATES PATENT OFFICE.

WACLAW KENSTOWICZ, OF CHICAGO, ILLINOIS.

ROTARY BRUSH.

1,212,360.

Specification of Letters Patent. Patented Jan. 16, 1917.

Application filed October 22, 1915. Serial No. 57,294.

To all whom it may concern:

Be it known that I, WACLAW KENSTOWICZ, a citizen of the United States, residing at Chicago, in the county of Cook and State of Illinois, have invented certain new and useful Improvements in Rotary Brushes, of which the following is a specification.

This invention relates to rotary brushes which are operated by a motor, and its object is to provide a novel and improved brush of this kind which is so mounted and supported that it may be used in various positions, and easily handled and controlled.

The object stated is attained by means of a combination and arrangement of parts to be hereinafter described and claimed, and in order that the same may be better understood, reference is had to the accompanying drawings, in which—

Figure 1 is a side elevation of the invention partly in section; Fig. 2 is a plan view, partly broken away; Figs. 3, 4 and 5 are sectional views on the lines 3—3, 4—4 and 5—5, respectively, of Fig. 2, and Fig. 6 is a perspective view of a wiper which may be substituted for the brush.

Referring specifically to the drawings, 10 denotes a suitably constructed casing carrying the brush and the motor for operating the same, and provided with a handle composed of separable sections 11 suitably connected so that the handle may be lengthened or shortened according to the height and location of the surface to be operated on. 35 If the brush is used for ceiling work, the handle is inserted telescopically into a bottom piece 12 mounted on a caster wheel 13, so that the device may be wheel-supported while in operation. A set screw 14 secures 40 the handle to the bottom piece 12.

The casing 10 is trough-shaped and constructed of sheet metal, and it is pivotally supported between the branches 15 of a fork, the stem 16 of which latter is connected 45 to the top one of the handle sections 11. The connection is made by a sleeve 17 secured to the top handle section, into which sleeve the fork stem extends, with a spring 18 interposed between the opposite ends of the handle section and the fork stem. The fork stem and the fork branches are separably connected as shown in Fig. 5 (an ordinary screw joint being employed). A head 19 on the lower end of the fork stem prevents 50 withdrawal from the sleeve 17.

The casing 10 has pivots 20 at its ends for

connection to the fork branches 15, so that it may be swung to place the brush in various positions according to the location of the surface to be operated on. Fig. 1 60 shows in full lines the casing adjusted to locate the brush at the top, so that a ceiling may be operated on, and in dotted lines the casing is shown tilted forward to bring the brush to the side for operating on a wall. 65 For locking the casing to the fork, the branches of the latter have curved arms 21 provided with slots 22 through which pass bolts 23 fast on the end walls of the casing and carrying wing nuts 24.

Adjacent to the end walls of the casing 10, the latter contains a transverse partition 25, dividing the casing into two compartments, one wide and the other narrow, the latter being next to the last mentioned end wall 75 of the casing. The wide compartment is closed at the top for about one half of its width, the cover 26 being preferably integral with the side wall of the casing. The narrow compartment is provided with a 80 hinged lid 27 held closed by an ordinary spring catch 28.

In the narrow compartment is housed a spring motor, the spring of which is indicated at 29. This spring, through a train 85 30 of gears operates a shaft 31 which actuates a cylindrical brush 32. The bristles of the brush are mounted on a wooden core 33 having at one end a central aperture 34 which is squared to receive the squared end 90 of the shaft 31. The partition 25 has an opening 35 through which the shaft 31 passes. The opposite end of the core 33 has a short spindle 36 seating in a bearing 37 on the adjacent end wall of the casing 10. The 95 bearing 37 has a hinged cover 38 to permit removal of the brush, and a latch pin 39 locks the lid in closed position. To remove the brush, the pin 39 is taken out, and the brush is shifted endwise until the end of the 100 shaft 31 is clear of the aperture 34, after which the brush can be lifted out of the casing upon swinging the bearing cover 38 open. A reversal of this operation positions the brush in the casing and couples it to the shaft 31. The pin 39 extends across the end of the spindle 36 and thus locks the brush against endwise movement in this direction, thereby preventing the brush from 105 being uncoupled from the shaft 31.

The spring motor hereinbefore described drives the brush 32 when the same is coupled

to the shaft 31, and in order to control the speed of the motor, the same is provided with a friction brake 40 having an operating line 41.

5 Although a spring motor is shown for operating the brush 32, it is to be understood that an electric motor may be employed with equal facility.

10 The compartment of the casing 10 in which the brush 32 is mounted will be partly filled with water, as shown in Fig. 4, in which the brush is immersed, an overflow spout 42 being provided to maintain a proper level. This spout maintains such a 15 water level in the casing, that when the latter is tilted to the dotted line position in Fig. 1 the water level will not be above the opening in the compartment through which the brush projects. The brush projects a 20 sufficient distance so that it may come in contact with the surface to be operated on. A rubber wiper or squeegee shown at 43 in Fig. 6 may be substituted for the brush 32, for wiping the ceiling or walls dry, the 25 water in the brush compartment of the casing 10 being first run out.

The brush may be used for cleaning, as well as for coating walls and ceilings, and it is easily handled and controlled. The 30 spring 18 provides a cushioned support for

the brush and holds the same pressed against the surface being operated on.

The opening 44 in the top 26 of the casing 10 through which the brush 32 projects has opposite outstanding guard flanges 45 which diverge and serve to gather any liquid dropping from the ceiling or squirted from the brush, and direct the same back into the casing. The outer flange 45 carries a rubber wiper strip 46 which may be used 45 for wiping off any excess liquid from the surface to be cleaned or coated.

I claim:

The combination of a handle, an elongated receptacle carried by the outer end of the handle and adjustable angularly with respect thereto, a rotary brush mounted in the receptacle at one end thereof, the top of the receptacle being closed throughout a substantial portion of its length, leaving a top opening at the end of the receptacle carrying the brush, said brush being located partly beneath the top of the receptacle, the depth of the receptacle being less than the diameter of the brush, and the working portion of the brush projecting through the aforesaid top opening.

In testimony whereof I affix my signature.

WACLAW KENSTOWICZ.
